United States Patent Office

Des. 194,447
Reissued Jan. 22, 1963

194,447

DISPLAY STAND

Sheldon C. Brooks, Minneapolis, Minn., assignor to Tri-State Displays, Inc., Minneapolis, Minn.

Filed June 13, 1962, Ser. No. 70,536

Term of patent 14 years

(Cl. D80—9)

FIG. 1

FIG. 2

FIG. 3

I claim:

The ornamental design for a display stand, as shown.
